UNITED STATES PATENT OFFICE.

EDWARD G. THOMAS, OF TOLEDO, OHIO, ASSIGNOR TO TOLEDO SCALE COMPANY, OF TOLEDO, OHIO, A CORPORATION OF NEW JERSEY.

PIVOT RETAINER.

Application filed September 2, 1925. Serial No. 53,968.

This invention relates to means for mounting knife edge pivots such as are employed in weighing scales and analogous machines, and, while I have shown the device as used for the purpose of securing a pivot to a scale lever, it is also adapted for affixing pivots to other parts of machines.

One of the particular objects of this invention is the provision of inexpensive and efficient means for securely holding a pivot bar in place in a lever or other machine element.

Another object of the invention is to provide means for so mounting a pivot that it is reliably held against accidental shifting but nevertheless is readily removable for purposes of repair and replacement.

Still another object is the provision of an inexpensive and efficient combined pivot supporting key and thrust bearing.

Other objects and advantages will be apparent from the following description, in which reference is had to the accompanying drawings illustrating preferred embodiments of my invention and wherein similar reference numerals designate similar parts throughout the several views.

In the drawings:—

Figure I is an elevational view of a portion of a lever with two pivots secured thereto, according to my invention;

Figure II is an enlarged vertical sectional view through the lever showing the preferred form of the pivot retaining means;

Figure III is a fragmentary elevational view of that portion of the lever illustrated in Figure II;

Figure IV is an enlarged detail view of the pivot retaining key;

Figure V is an end view of the key illustrated in Figure IV;

Figure VI is a fragmentary view of a portion of a lever showing the openings adapted to receive the pivot and retaining keys;

Figure VII is a sectional view similar to Figure II showing a modified form of the device;

Figure VIII is a fragmentary elevational view of the parts illustrated in Figure VII; and

Figure IX is a fragmentary elevational view of one end of a lever showing another form of the device.

Referring to the drawings in detail, the lever 1 is of a type used in scales designed for

weighing comparatively heavy loads, and comprises a vertical web having laterally extending flanges along its upper and lower sides, making it of substantially I-beam section. The portions of the web through which the pivots extend are formed with integral bosses 2 and 3, which are preferably about the depth of the flanges and are merged with them, as illustrated in Figure I. The bosses 2 and 3 are also provided with integral laterally projecting portions 4 which form suitable co-operating surfaces for the pivot retaining keys, which construction will be hereinafter described in further detail.

In the form of the device particularly illustrated in Figures II, III and VI a cylindrical opening 5 is first drilled through the boss with the axis of this opening perpendicular to the central vertical plane of the lever. Another cylindrical opening 6 is then bored through the boss, the axis of the latter opening making an acute angle with the vertical plane of the lever of about 88° or 89°. Another opening 7 is then bored through the lever joining the openings 5 and 6, the axis of opening 7 being perpendicular to the central vertical plane of the lever.

In the assembly of the pivot a cylindrical bar 9 having a V-shaped groove of uniform depth is first placed in the opening 5 in the lever and the pivot bar 10 inserted in the opening 7, the knife edge of the pivot bar being received into the V groove of the bar 9. The cylindrical pivot retaining key 12 is then driven into place in the opening 6 adjacent the back of the pivot bar 10 and serves to wedgingly hold the pivot bar in place in the lever, the wedging effect being obtained by drilling the opening 6 at an acute angle with the plane of the lever.

Milled or otherwise formed in the retainer is a groove 13 which is progressively deepened from one end of the retainer to the other, so that when the retainer is properly inserted in the lever in frictional engagement with the lever and pivot the grooved face thereof will be perpendicular to the plane of the lever and in perfect aligned engagement with the back surface of the pivots. The ends of the bar 9 are cone-shaped so as to provide anti-friction thrust members which are adapted to cooperate with the bearings that engage the knife edge pivot.

The portions 4 of the lever 1 adjacent the pivot retaining key 10 are preferably en-

larged to provide suitable engaging surface for the pivot retainer, so that any tendency of the retaining key to loosen up will be practically precluded because of the large frictional surface between the key and the lever.

In the modification shown in Figures VII and VIII the pivot bar 10' is substantially polygonal in cross section so as to provide two knife edges, either of which may be used by 10 simply inverting the bar. The cylindrical bar 9' is substantially identical in construction with the bar 9 shown in Figure II, but the retaining key 12' is provided with a V-shaped groove 13' which is progressively 15 deepened from end to end, the walls of the groove being adapted to co-operate with the knife edge of the pivot bar 10' to hold the latter in place in the lever. In this form of the device, should the knife edge become worn 20 it is only necessary to drive out the retainer 12', invert the pivot bar and replace the retainer, and a new knife edge is ready for use.

In the modified form of my invention illustrated in Figure IX the back of the pivot bar 25 10'' is substantially rectangular in shape, thus necessitating a rectangular groove in the retainer 12'', so that the latter may properly co-operate with the back of the pivot bar to hold it in place.

30 The embodiments of my invention herein shown and described are to be regarded as illustrative only, and it is to be understood that the invention is susceptible to variation, modification and change within the spirit and 35 scope of the subjoined claims.

Having described my invention, I claim:

1. In a device of the character described, 40 in combination, a lever having an opening, the walls of said opening being non-parallel, a pivot bar inserted in said opening, and means including a cylindrical member having a progressively deepened channel therein

adapted to co-operate with the pivot bar and the walls of said opening for wedgingly retaining said pivot in place.

2. In a device of the character described, 45 in combination, a lever having an opening, the walls of said opening being non-parallel, a pivot bar, a grooved cylindrical member in said lever adapted to receive said pivot bar, and means including a cylindrical member having a groove progressively deepened from end to end adapted to be inserted in the opening in said lever and engage said pivot bar to wedgingly retain the latter in proper 50 position in the lever.

3. In a device of the character described, 55 in combination, a lever having a plurality of inter-connected cylindrical openings, the axis of one of said openings being non-parallel with the axes of the other of said openings, a pivot bar inserted in said openings, a channeled cylindrical member in one of said openings and adapted to receive the knife edge of said pivot bar, and means including 60 a cylindrical member having a channel progressively deepened from end to end adapted to frictionally engage and co-operate with said pivot bar to hold same in place in said lever.

4. In a device of the class described, in 65 combination, a lever having an opening, the walls of said opening being non-parallel, a pivot bar, a channeled cylindrical member having cone-shaped extremities positioned in 70 the opening in said lever and adapted to receive said pivot bar, and retaining means for said pivot bar including a cylindrical member having a groove therein progressively deepened from end to end and adapted to frictionally engage the pivot bar and maintain the latter in substantially perpendicular relation with the normal plane of the lever.

EDWARD G. THOMAS.
